PLASTERER'S FLOAT AND TROWEL

Edward Stabbert, Tacoma, Wash.

Application May 23, 1938, Serial No. 209,434

8 Claims. (Cl. 72—136)

This invention relates to improvements in plasterers' floats and trowels.

The primary object of the invention is to provide a tool for use by plasterers, which will serve both as an angle float and angle trowel and which is so constructed and shaped that it will be convenient to use, will not mar the plastered surface in any way and will permit the working of the plaster right up into the corner without the end of the tool digging into the plastered surface adjoining the corner.

A further object of the invention is to provide a tool of this kind in a simple and practicable form and of such material that it will have long wearing qualities and will not stain the plaster.

The foregoing and other more specific objects of the invention will be made apparent in the course of the following detailed specification, reference being had to the accompanying drawing 20 wherein:

Fig. 1 is a plan view of my improved tool.

Fig. 2 is a side or edge view of my tool.

Fig. 3 is an end view, a part of the handle being shown broken away and in cross section to disclose the mounting of one of the brace rods therein.

Referring now with more particularity to the drawing, my tool comprises the rectangular, flat base plate 5 upon which is mounted a handle 6 extended longitudinally on the base. This handle 6 is of the usual type and shape used on plasterers' floats and includes the downwardly turned ends 7 which are secured by flat head screws 8 (or other suitable means) to the base.

Along one margin of the base a side flange 9 is turned upwardly at right angles as shown, forming a sharp angle 10 at its junction with the base. This side flange is braced against the action of lateral stresses by means of the brace rods 11—12 which are secured, as by welding at 13, to the inner side of the side flange and which extend inwardly therefrom parallel with the base 5 and penetrate the ends 7 of the handle 6. These handle ends 7 have transversely extended bores 14 which receive and pass the inner ends of the brace rods 11—12 and these bores are enlarged on the sides remote from the side flange 9 to form sockets 15 wherein are mounted the screw type plugs 16. The inner ends of the brace rods 11—12 are threaded as at 17 and the plugs 16 are screwed thereon and drawn tight in the sockets 15. As a result, the brace rods 11—12 are rigidly supported and the side flange 9 is so connected and supported by the handle

6 that no flexing or weaving action of the flange can take place under any circumstances.

While it is considered that the base 5 and the side flange 9 are preferably made integrally of one piece of tempered steel, since it has been found that only this material has the requisite wearing qualities for a tool of this kind, nevertheless the base and flange may be formed separately, and of different materials, if found expedient, and the two elements then riveted 10 or otherwise secured together. Heretofore, such materials as wood and aluminum have been employed but these wear very rapidly in use and after a short time the corner at the working edge of the tool is worn away to the point that 15 a clean angle or corner can no longer be formed in the plaster. The use of steel is further recommended for the reason that this material has no tendency to stain the plaster.

The use of steel for floats of this kind has 20 not hitherto been possible since it, of course, has at least a measure of flexibility and, consequently, the edge of the float would have a tendency to flex and thus prevent the proper use of the tool in a corner. However, my invention 25 provides the brace rods 11—12 which positively brace and support the side flange of the tool and permit the use of this desirable material. The flexibility and resiliency of the steel used is actually put to an advantageous use in my 30 invention. It will be noted that a substantial lateral portion of the base 5 opposite to the side flange 9 is entirely free and unsupported insofar as the handle 6 is concerned. As a result this portion of the base 5 may bend and 35 flex as may be necessary in use and in order to prevent its digging into a wall or ceiling surface while working in the adjacent corner.

Referring to Figure 1, it will be noted that the side flange 9 is bent slightly and stands outwardly from a straight line at its center 18. The opposite end portions of the side flange thus angle inwardly from the straight line as shown, and when either of these end portions is rested against an adjacent wall while trowelling the 45 corner, the opposite end portion will stand outwardly from the wall a substantial distance. Therefore, by so manipulating the device that the trailing end of the side flange 9 engages the wall (or ceiling) the opposite frontal end 50 will stand away and cannot dig into the plaster. This action greatly facilitates the proper working of the plaster to an even line and clear up into the corner.

As a further aid to thus preventing the mar- 55

ring of the plaster by the frontal or leading edge of the tool, the ends of the side flange 9 are beveled off from their free margins toward the base 5 as indicated at 19.

5. It is understood that I may make changes in the structure and assembly herein specified, provided that such changes fall within the spirit and the scope of the appended claims.

Having thus completely disclosed my invention, 10 what I claim as new and desire to secure by Letters Patent is:

1. A plasterer's float and angle trowel comprising a flat base, a flange turned upwardly along one lateral margin of the base, a handle secured 15 to the base, and rods extended between the flange and the handle and effective to rigidify the said flange.

2. A plasterer's tool comprising a base member of flexible material, a flange formed integral- 20 ly with the base member and turned at right angles along one side thereof, a handle secured to the base parallel with the flange, and rods extended between the flange and the handle.

3. A plasterer's tool comprising a brace member, a flange formed integrally with the base member and turned at right angles along one lateral margin of the base, a handle secured to the base parallel with the said flange and in spaced relation thereto, and rods secured between 25 the flange and handle and extended parallel with and above the plane of the base.

4. A plasterer's tool comprising a flat rectilinear base member, a flange formed integrally with the base member and turned upwardly at right 30 angles along one margin of the same, a handle

secured to the base parallel with the flange and spaced from the opposite margin of the base member to permit flexing action of that portion of the base member, and means connecting the flanged portion of the base to the handle in a 5 rigid manner.

5. A plasterer's tool comprising a flat and rectangular base, a flange turned upwardly at right angles along one lateral margin of the base, and the said flange being formed of angularly ex- 10 tends faces meeting at a point of maximum width of base toward its center.

6. A plasterer's tool comprising a flat and rectangular base having a flange turned at right angles along one lateral margin, the said flange 15 being formed of inclined faces, the base tapering from the intersection of the faces toward the ends, whereby one portion of the flange may be brought into contact straightly with a wall 20 while the opposite end stands outwardly therefrom.

7. A plasterer's tool comprising a flat rectangular base and a flange turned upwardly along one lateral margin of the base, the said flange being bent medially to stand outwardly 25 from the base and to extend at opposite gradual angles from said medial portion, and the ends of the flange being beveled off to the base.

8. A plasterer's tool according to claim 6, 30 wherein the base is of flexible metal, a handle on the same side of said base as said flange, and rod means above the base extending from the flange to said handle.

EDWARD STABBERT. 35
